United States Patent Office.

WILLIAM WELLS, OF SALEM, MASSACHUSETTS, ASSIGNOR TO HIMSELF,
E. B. HORTON, AND DAVID BUFFUM, OF SAME PLACE.

Letters Patent No. 106,298, dated August 9, 1870.

IMPROVEMENT IN BOX OR CASE FOR HOT-BEDS.

The Schedule referred to in these Letters Patent and making part of the same.

To all persons to whom these presents shall come:

Be it known that I, WILLIAM WELLS, of Salem in the county of Essex and State of Massachusetts, have invented a new and improved Box or Case for Hot-Beds; and that the following description, taken in connection with the accompanying drawing, is a full and complete specification of the same, wherein I have set forth the nature and principles of my said invention, together with such parts as I claim and desire to have secured to me by Letters Patent.

The present invention relates to hot-bed cases; and

The invention consists in constructing the interior of the box or case upon either one or more sides, to reflect the sun-rays within the box, and thus the more perfectly subject the hot-bed and plants contained in it to their action.

Also, in combination with the above, the invention consists in arranging the reflecting surface or surfaces so that they can be adjusted in position within the box, as occasion may require.

In the accompanying drawing, my improved hot-bed box is illustrated—

Figure 1 being a plan or top view of the same.

Figure 2, a transverse vertical section in plane of line $x x$, fig. 1.

Figure 3, a horizontal section in plane of line $y y$, fig. 2.

Figure 4, an isometrical perspective view.

A in the drawing represents a hot-bed case or box, consisting of parallel side pieces B, joined together by end pieces C, with the whole covered by an inclining top or lid, D.

This lid D is hinged to one side of the box A, so as to be opened or closed, and it is constructed of a frame, E, in which is secured a pane of glass, F, in any suitable manner.

G, a sheet or plate of tin, arranged within the box A, against one of its end pieces C.

This sheet-tin G, at its lower edge a , is secured by hinges b to the end piece C, but its upper edge is free to be brought up against the said end-piece, or to be set at an angle of inclination with regard thereto, more or less great.

c , a stem fastened to tin G near its upper edge. This

pin or stem c projects through the end piece C outside of the box, and is provided, for convenience in adjusting the reflector-tin G within the box. In figs. 2 and 3, the reflector-tin G is shown, by dotted lines, as at various angles of inclination.

By the sheet tin G, the rays of light, passing through the glass top and impinging on the tin, are reflected thereby within the box, and, according to its adjustment, the direction in which they are thrown by reflection is changed, and thus, as is obvious, with a proper adjustment of the tin, they can be thrown directly upon the hot-bed and its plants, securing an increased heat and light thereto, and a more rapid development and growth of the plant.

By having the reflecting-surface adjustable, it is obvious the reflection of light and heat can be regulated to suit the inclination of the sun-rays, and, as is obvious, either to reflect them about the interior of the box, or to throw them out, according as the bed and plant may require.

In lieu of a tin reflecting-surface for the box, other forms of reflecting-surfaces may be employed, and more than one or all of the interior surfaces of the box may be constructed as reflectors.

In lieu of hinging the reflector at its lower edge, it may be hinged at its upper edge, but it is preferable to hinge it at its lower edge.

Having thus described my invention, I will state my claims as follows:

What I claim as my invention, and desire to secure by Letters Patent, is—

1. A hot-bed, box, or case, constructed with a reflecting-surface or surfaces, substantially as described, for the purpose specified.

2. In combination with the above, said surface or surfaces, when arranged for adjustment, substantially as and for the purpose described.

The above specification of my invention signed by me this 4th day of March, A. D. 1870.

WILLIAM WELLS.
